CAB FOR FARM MACHINERY

Elmer F. Stucky, Hesston, Kans.

Application August 25, 1958, Serial No. 52,354

Term of patent 14 years

(Cl. D14—3)

Fig. 2.

Fig. 1.

Fig. 1 is a perspective view of the front and one side of a cab for farm machinery, showing my new design; and

Fig. 2 is a perspective view of the front and opposite side of a cab for farm machinery.

The dominant features of my design reside in the portions shown in full lines.

I claim:

The ornamental design for a cab for farm machinery, as shown and described.
